UNITED STATES PATENT OFFICE.

GEORGE W. FRENCH, JR., OF DANVERS, MASSACHUSETTS.

CLOTH-DISTRIBUTER.

1,232,017.

Specification of Letters Patent. Patented July 3, 1917.

Application filed November 30, 1914. Serial No. 874,941.

To all whom it may concern:

Be it known that I, GEORGE W. FRENCH, Jr., a citizen of the United States, and resident of Danvers, in the county of Essex and 5 State of Massachusetts, have invented certain new and useful Improvements in Cloth-Distributers, of which the following is a specification.

The object of the present invention is to 10 provide a distributing apparatus for laying cloth in pits in which the cloth is to be soaked in a dye, or a bleaching solution, or a washing solution, or in fact in any liquor which may be useful in the treatment of 15 the cloth. It is to be understood that the apparatus with which my invention is concerned acts upon finished cloth in the web. The primary purpose of the apparatus is to distribute the cloth in zigzag plaits in such a 20 way that after the treatment in the pit is completed it may be withdrawn without being snarled and without being tied into knots. The particular object of the invention is to provide a simple mechanism which 25 will give the leader, or guide, through which the cloth is conducted in the distributing a back and forth movement in two directions at right angles to each other with automatic reversals at the end of each movement and 30 without necessitating the use of reversing mechanisms of any sort.

The particular nature of the invention and the improvements in which the same consist will be fully understood from the 35 description following in connection with the drawings. In the drawings,

Figure 1 is a plan view of a distributing mechanism or distributer containing the form of the invention which at the present 40 time I consider to be preferable to others.

Fig. 2 is an elevation of the distributer over the pit in which the cloth is laid for the required treatment.

Fig. 3 is an isometric view of the distributor.

Fig. 4 represents a sectional view of one of the travelers and a perspective view of the yoke associated therewith to enter the threads of the screw.

In the drawings A A A A represent four shafts arranged in the form of the sides of a rectangle and geared together at three corners of the rectangle by miter gears B-B, B-B. A pulley F of one of the 55 shafts serves to receive the motive power

through a belt, which power is transmitted to all of the shafts in unison.

For the purpose of this description the four shafts shown may be considered as two pairs of shafts, each two which form opposite sides of the rectangle being one pair. On each shaft is mounted a traveler C, the two travelers on opposite shafts constituting a pair and those of each pair being connected by spacing rods D-D. The rods 60 of one pair of travelers cross those of the other pair and form a rectangular inclosure. A spout or leader E passes through this rectangular space and is embraced by all four of the rods D. The leader E is hung 65 by a gimbal joint G adjacent to a guide roll H over which the cloth is laid. By virtue of this gimbal joint the delivery end of the leader may be swung in any direction so as to follow the different movements of the 70 travelers and guide rods.

The shafts A have grooves I, I' formed on opposite inclinations and crossing one another, thus constituting in effect crossed threads which are jointed together adjacent 80 to the ends of the shafts. The travelers or followers C are all alike, and one of them is shown in detail on an enlarged scale in Fig. 4. In construction the follower is essentially a sleeve surrounding and adapted 85 to slide on one of the shafts. It contains a yoke J curved to conform to the shaft at the base of the grooves or threads and otherwise of such dimensions as to fit freely in such grooves. It has a stem or stud J' which 90 occupies a socket in the follower and forms a swivel whereby the yoke may swing as required in passing from one groove to the oppositely inclined groove at the points where such grooves merge into one another. 95 The crossed threads of the shafts cause their respective followers to travel back and forth from end to end and to reverse directions of movement when arriving at each end of their travel, because the thread I', for instance, which drives the follower in one direction merges at its end into the thread I, extending in the opposite direction, so that the follower passes from the influence of the thread I' to that of the thread I and the reverse, at each end of the travel, without shock and without necessitating any change in direction or speed of rotation of the shaft. The distributer device is placed over the mouth of a pit K.

It will be understood that the swinging end of the leader is given movements which are the resultant of the back and forth movements in directions at right angles to 5 one another of the carriers which are formed by the two pairs of nuts C and the coupling rods D. As one pair of shafts travels at a higher speed than the other pair, as is indicated by the difference in diameter of the 10 gears B of each couple, the cloth which issues from the leader is led in long zigzags which pile up on one another in successive layers.

When cloth is laid in this zigzag manner, 15 the adjacent and contacting plaits are so inclined to one another that there is no possibility of them being twisted and carried about one another in any such way as would cause snarls, wherefore the cloth may be 20 readily withdrawn from the pit after the treatment to which it is subjected in the pit has been completed.

What I claim and desire to secure by Letters Patent is:

25 1. A cloth distributer comprising a leader movable in any direction, two carriers movable in directions transverse to one another each engaged with the leader and both being simultaneously moved, whereby to give 30 the leader motions which are resultants of those of both carriers, and threaded shafts for moving the carriers, said shafts having crossed threads which merge into one another at the ends of the shafts, whereby the 35 carriers are reversed at each end of their travel without necessitating change in the direction or speed of rotation of the shafts.

2. A cloth distributer comprising cross-threaded screw shafts arranged on the four 40 sides of a rectangle and geared to rotate in

unison, a nut carried by each screw and caused by the cross threads thereof to reverse its direction of motion at each end of its travel, tie members connecting the nuts on opposite sides of the rectangle together, each pair of nuts and their tie members forming a carrier, and a leader for cloth engaged simultaneously by both carriers and moved thereby in directions which form the resultants of the simple movements 50 of the carriers.

3. A cloth distributer comprising guides for a cloth web one of said guides being movable in a direction substantially at right angles to the other, and both acting on the 55 web at the same time, and screw shafts arranged to operate said guides, said shafts having crossed threads which emerge into one another at the ends of the shafts, whereby the carriers are reversed at each end of 60 their travel without necessitating change in the direction or speed of rotation of the shafts.

4. A cloth distributer comprising a plurality of guides, one of which is movable 65 back and forth in a path transverse to the other, and both of which act simultaneously to control the direction of feed of the cloth, and means for continuously moving said guides in their appointed paths and automatically reversing their motion, the resultant of the motions of said guides being the lines in which plaits of cloth are laid.

In testimony whereof I have affixed my signature, in presence of two witnesses.

GEORGE W. FRENCH, JR.
